UNITED STATES PATENT OFFICE.

FREDERICK C. REHM, OF DETROIT, MICHIGAN, ASSIGNOR TO CHICAGO HOSIERY CO., OF DETROIT, MICHIGAN, A, CORPORATION OF MICHIGAN.

KNITTING-MACHINE.

1,200,985.

Specification of Letters Patent. Patented Oct. 10, 1916.

Application filed August 11, 1915. Serial No. 44,853.

To all whom it may concern:

Be it known that I, FREDERICK C. REHM, a citizen of the United States, residing at Detroit, in the county of Wayne and State of Michigan, have invented certain new and useful Improvements in Knitting-Machines, of which the following is a specification.

My invention relates to improvements in knitting machines adapted to produce a knitted web having loops extending from one face thereof, of the class disclosed in my previous Patents Nos. 535,461; 619,840 and 839,200 to which reference may be had.

The object of my present invention is to provide a novel, simple and efficient means whereby two separate threads may be controlled and fed to the needles and the loop-forming devices in such a manner as to cause the needles to act upon both threads at certain intervals and to act upon but one of the threads at certain other intervals; the needles producing a plain knitted web having no loose loops extending therefrom when the needles act upon but one of the threads, and the needles acting in conjunction with the loop-forming devices and producing a knitted web having the loose loops extending from one face thereof when the needles act upon both threads.

Accordingly, my invention includes a thread delivery member movable into and from an operative position and controlling the thread which produces the said loose loops, the loop-forming thread being directed to the needles and the loop-forming devices for the production of the loose loops when the member is in the operative position, and the loop-forming thread being prevented from reaching the needles and the loop-forming devices for the production of the plain web by the other thread when the member is in the inoperative position; and my invention includes, further, an automatic means to move the said member into and from its operative position.

With this object in view, my invented machine consists of the elements and the combinations of them hereinafter fully described and claimed.

In the accompanying drawings, illustrating my invention, Figure 1 is a side elevation of a knitting machine embodying my invention. Fig. 2 is a sectional detail showing the wheel for controlling the loop-form-

ing thread and adjuncts. Fig. 3 is a sectional detail showing a part of the pawl and ratchet mechanism. Fig. 4 is a plan view of the machine. Fig. 5 is a detail, as seen from the line 5—5 of Fig. 4, showing the thread feeding devices and adjuncts. Fig. 6 is a vertical section through the machine. Fig. 7 is a sectional detail showing the member for delivering the loop-forming thread to the needles, the member being shown in the operative position by full lines and in the inoperative position by dot-and-dash lines.

Referring to the drawings, the frame of the machine comprises a lower plate 2 and an upper plate 3, supporting legs 4 for the lower plate 2, and a housing 6 rising from the lower plate 2 and supporting the upper plate 3.

Supported by a bearing on the housing 6 is a shaft 7 carrying a driving pulley 8 which is connected to a gear wheel 9 on the shaft 7. The gear wheel 9 is in mesh with a gear wheel 10 which rotates on a shaft 11 which turns in the housing 6. The hub 12 of the gear wheel 11 carries a gear wheel 13, hereinafter referred to, which is adapted to be engaged by a clutch collar 14 splined on the shaft 11, whereby when the collar 14 is engaged with the gear wheel 13, and power is applied to the pulley 8, the shaft 11 will be rotated. The shaft 11 carries a bevel gear wheel 15 coaxing with a similar wheel 16 which is mounted to rotate horizontally in the plate 3.

The gear wheel 16 carries the needle cylinder 17 having the circular set of knitting needles 18 arranged to slide vertically therein. The needles 18 are adapted to be operated by the knitting cams 19 which are fixed on the plate 3, whereby, when the needle cylinder 17 is rotated by the mechanism previously described, the cams 19 will reciprocate the needles 18 to effect the knitting operation, in the usual well known manner.

Fixed on the needle cylinder 17 is a ring 20 carrying the usual radially-movable web holders 21 which are actuated in the usual manner by the cams of a cam ring 22 which is supported on the ring 20 and is prevented from being rotated therewith by a post 23 rising from the fixed plate 3 and to which the cam ring 22 is connected.

The post 23 carries an arm 24 which sup-

ports a ring 25. The ring 25 surrounds the upper portion of the set of needles 18 and forms a latch guard therefor and is provided with a thread delivery eye 26 directly above the knitting cams 19 by means of which a thread 27 may be fed to the needles 18 to be acted upon thereby in the usual manner during the knitting operation.

The construction and operation of the parts thus far described are common and well known and no detailed description or illustration thereof is deemed necessary herein.

Secured on the ring 20 is a ring 28 having radial slots formed therein in which a circular set of loop forming devices 29 are mounted to slide radially between the needles 18. The devices 29 are provided with upwardly projecting butts which enter a camway 31 formed in a ring 32 which is supported on the ring 28 and which is prevented from rotating with the ring by the post 23 to which the ring 32 is connected. The contour of the camway 31 is such that, during the rotation of the needle cylinder 17 and therewith the ring 32, the devices 29 are maintained normally withdrawn from between the needles 18, and are projected inwardly between the needles where the needles are lowered to form the stitches, and are withdrawn from between the needles immediately following the raising of the needles after the formation of the stitches. It will therefore be understood that when a thread 33 is fed to the needles 18 above the eye 26 and above the devices 29, as shown in Fig. 5, both threads 27 and 33 will be knitted into the fabric and that the thread 33 will be drawn down between the devices 29 and into the fabric and thus produce the loops 34 on the inner face of the tubular knitted fabric; and it will also be understood that after the stitches have been formed and the needles 18 have been raised to the normal level, the devices 29 will be withdrawn from between the needles 18 to discharge the loops, after the formation thereof, during the knitting of each course of stitches.

The camway 31 is substantially the same as the camway "18" shown in my previous Patent No. 839,200, and the operation of the devices 29 with respect to the needles 18 is substantially the same as the parts "5" and "16", respectively, shown in my Patent No. 839,200, excepting that in the present case the set of devices 29 and the needle cylinder 17 rotate and are operated by fixed cams, whereas, in the previous case, the loop forming devices and the needle cylinder do not rotate and are operated by rotating cams, the difference being a reversal of the parts.

The loop forming thread 33 is fed to the needles 18 through a tubular thread delivery

member 34 secured to the inner end of an arm 35 which is pivoted, at 36, to a bracket 37 secured on the stationary cam ring 32. This arm 35 and therewith the thread delivery member 34 are movable on the pivot 36 from an operative position, shown by full lines in Fig. 7, to an inoperative position, shown by dot-and-dash lines in Fig. 7. When the member 34 is in the operative position shown in Figs. 5 and 7, the thread 33 is fed to the needles 18 between the hooks thereof and the tops of the devices 29, as clearly shown in Fig. 5, and the loose loops are produced on the inner face of the tubular fabric, as previously explained. When, however, the arm 35 and therewith the member 34 are in the inoperative or dot-and-dash line position, shown in Fig. 7, the thread 33 is prevented from reaching the needles 18 between their hooks and the devices 29, and a plain knitted web having no loose loops formed thereon is produced by the needles 18 acting on the thread 27 alone.

The loop forming thread 33, while being fed to the needles 18, is guided not only by the tubular member 34 but also by the wall of a slot 38 in the ring or latch guard 25, the slot having a wide upper portion 39 and a narrow lower portion 40, as shown in Fig. 5, the thread 33 entering the narrow portion 40 when the member 34 is lowered to the operative position, and the thread 33 entering the wide upper portion 39 when the member 34 is raised to the inoperative position. The narrow portion 40 of the slot 38 insures the proper delivery of the thread 33 to the needles 18 when the member 34 is in the operative position; and the wide portion 39 of the slot 38 gives free play to the thread 33 and prevents any liability of it being caught by the needle hooks and knitted into the fabric when the member 34 is in the inoperative position.

I shall now describe the means to automatically lower and raise the arm 35 and the thread delivery member 34 into and from the operative position at certain predetermined intervals during the operation of the machine. Mounted to turn on a shaft supported in the housing 6 is a gear wheel 41 which is actuated by the gear wheel 13 hereinbefore referred to. The gear wheel 41 is connected by a link 42 to a member 43 which is mounted to rock on a shaft 44 in the housing 6, whereby, during the rotation of the gear wheel 41, the member 43 will be rocked. The member 43 carries a pivot stud 45 having a pawl 46 pivoted thereon adapted to engage a ratchet wheel 47 which is mounted to turn on a shaft 48 rotatably fitted in bearings in the housing 6. Loosely mounted on the shaft 48 adjacent to the ratchet wheel 47 and secured thereto is a sprocket wheel 49 which carries a pattern chain 50.

The rocking member 43 is always actuated during the operation of the machine and the pawl 46 is constantly in motion and in operative relation to the sprocket wheel 47 for the regular advancement of the pattern chain 50 at all times. Secured on the shaft 48 adjacent to the ratchet wheel 47 is a ratchet wheel 51 which, as will be presently described, is controlled by the pattern chain 50 and is actuated to turn the shaft 48 only at certain predetermined intervals. This ratchet wheel 51 is adapted to be actuated by a pawl 52 which is pivoted on the stud 45 of the rocking member 43. The pawl 52 has a lateral projection 53 which rests normally on the arm 54 of a lever 55 which is fulcrumed, at 56, in the housing 6. The lever 55 has an arm 57 provided with a lateral projection 58 which extends over the pattern chain 50, and the lever 55 has an arm 59 which is connected to one end of a spring 60. The other end of the spring 60 is connected to the housing 6, and the spring 60 acts upon the lever 55 to maintain its projection 58 down upon the pattern chain 50. The pattern chain 50 is provided with certain high links 61 which, when they pass under the projection 58 of the arm 57 of the lever 55, raise the arm 57 and lower the arm 54 supporting the pawl 52. When a high link 61 passes under the projection 58 the arm 54 and therewith the pawl 52 are lowered so that the pawl will engage a tooth of the ratchet wheel 51 and advance the ratchet wheel 51 and the shaft 48; and when the low links 62 of the chain 50 pass under the projection 58 the arm 54 and therewith the pawl 52 will be raised and the pawl will be prevented from actuating the ratchet wheel 51. It will thus be seen that the shaft 48 remains idle and is slightly turned at certain predetermined intervals, controlled by the pattern chain 50. The shaft 48 has a wheel 62 secured thereto which is provided with a notch or depression 63; and resting upon the wheel 62 is the downwardly-turned end of an arm 64 which is pivoted, at 65, in the housing 6. The end of the arm 64 is adapted to drop into the depression 63 when the depression is moved into registry with the arm 64, and the arm 64 is adapted to be raised from the depression 63 when the wheel 62 is turned to move the depression 63 out of registry with the arm 64. Pivoted to the arm 64 is the lower end of a rod 66, the upper end of which is pivoted, at 67, to the outer end of the arm 35 which carries the thread delivery member 34. The parts are constructed and related to each other so that when the arm 64 drops into the depression 63 the thread-delivery member 34 will be raised to the inoperative position, and that when the arm 64 is raised from the depression 63 the thread-

delivery member 34 will be lowered to the operative position. It will therefore be understood that while the depression 63 is in registry with the arm 64, the machine will produce a plain knitted web, and that while the depression 63 is out of registry with the arm 64, the machine will produce a knitted web having the loose loops extending therefrom, and it will also be understood that the relative lengths of the plain knitted web and the web having the loose loops extending therefrom are controlled by the pattern chain 50, and that the said lengths may be varied by varying the pattern chain. 70

The invention is especially adapted for use in hosiery machines for knitting stockings having loose loops extending from the inner face of the knitted fabric, for the reason that it is desired to have a plain knitted web at the junctures of the toe portions and leg portions of the stockings, where the stockings are knitted in a continuous tube and afterward cut, to present plain knitted fabric for the subsequent closing of the toe portions and the finishing of the ends of the leg portions of the stockings. 80

The rocking member 43 which actuates the pawls 46 and 52 has a gear sector 68 formed thereon which coacts with a gear wheel 69 which is loose on the shaft 11 for actuating the needle cylinder 17; and when the heel and toe portions of a stocking are knitted on the machine, the clutch collar 14 is moved from engagement with the gear wheel 13 and into engagement with the gear wheel 69 thereby causing the sector 68, and gear wheel 69 to reciprocate the shaft 11 and needle cylinder 17 in the usual manner for the production of the heel and toe portions 105 of the stockings. 100

I claim:

1. In a knitting machine, the combination of a set of needles, means operative to deliver two separate threads to said needles in a manner to cause said needles to act upon both threads and to act upon but one of them in alternate succession for the production of a knitted web, a set of loop forming devices adapted to produce loose loops of one of said threads extending from one face of said knitted web, only when both threads are being acted upon by said needles, and means to actuate said needles and said devices for the production of said web and said loops. 110

2. In a knitting machine, the combination of a set of needles, means to automatically deliver two separate threads to said needles in a manner to cause said needles to act upon both threads and to act upon but one of them in alternate succession for the production of a knitted web, a set of loop forming devices adapted to produce loose loops of one of said threads extending from one face of said knitted web, only when both threads are 120

being acted upon by said needles, and means to actuate said needles and said devices for the production of said web and said loops.

3. In a knitting machine, the combination of a set of needles, a set of loop forming devices, a thread delivery part arranged to deliver thread to said needles to be acted upon thereby independently of said devices for the production of a plain knitted web, a thread delivery member movable into and from an operative position and adapted to deliver thread to said needles and said devices to be acted upon thereby for the production of loose loops extending from one face of said knitted web, only when said member is in its operative position, and means to actuate said needles and said devices for the production of said web and said loops.
4. In a knitting machine, the combination of a set of needles, a set of loop forming devices, a thread delivery part arranged to deliver thread to said needles to be acted upon thereby independently of a plain knitted web, a thread delivery member movable into and from an operative position and adapted to deliver thread to said needles and said devices to be acted upon thereby for the production of loose loops extending from one face of said knitted web, only when said member is in its operative position, means to actuate said needles and said devices for the production of said web and said loops, and means to automatically move said member into and from its operative position.
5. In a knitting machine, the combination of a set of needles, a set of loop forming devices, a thread delivery part arranged to deliver thread to said needles to be acted upon thereby independently of said devices for the production of a plain knitted web, a thread delivery member movable into and from an operative position and adapted to deliver thread to said needles and said devices to be acted upon thereby for the production of loose loops extending from one face of said knitted web, only when said member is in its operative position, the wall of said slot coöperating with said member in delivering thread to said needles and said devices, and means to actuate said needles and said devices for the production of said web and said loops.

in its operative position, means to actuate said needles and said devices for the production of said web and said loops, a cam actuated by said means, and means operated by 50 said cam for moving said member.

6. In a knitting machine, the combination of a set of needles, a set of loop forming devices, a thread delivery part arranged to deliver thread to said needles to be acted upon 55 thereby independently of said devices for the production of a plain knitted web, a thread delivery member movable into and from an operative position and adapted to deliver thread to said needles and said devices to be acted upon thereby for the production of loose loops extending from one face of said knitted web, only when said member is in its operative position, means to actuate said needles and said devices for 60 the production of said web and said loops, a cam, a pawl-and-ratchet mechanism actuated by said means and actuating said cam, and means operated by said cam for moving said member.

7. In a knitting machine, the combination of a set of needles, a needle-latch guard adjacent to said needles and having a slot therein, a thread delivery part arranged to deliver thread to said needles to be acted upon 75 thereby independently of said devices for the production of a plain knitted web, a thread delivery member movable into and from an operative position and adapted to deliver thread to said needles and said devices to be acted upon thereby for the production of loose loops extending from one face of said knitted web, only when said member is in its operative position, the wall of said slot coöperating with said member 80 in delivering thread to said needles and said devices, and means to actuate said needles and said devices for the production of said web and said loops.

In testimony whereof I affix my signature 90 hereto.

FREDERICK C. REHM.
